Fig. 1 is a side elevational view of a trailer body showing my new design.

Fig. 2 also is a side elevational view opposite that shown in Fig. 1.

Fig. 3 is a rear elevational view of said body.

Fig. 4 is a front elevational view of said body.

Fig. 5 is a top plan view on a slightly reduced scale.

Fig. 6 is a side elevational view with the roof extension and the counter elements in folded position.

Fig. 7 is a side elevational view, on a slightly reduced scale, similar to Fig. 2 with the roof extension in folded position.

Fig. 8 is a rear elevational view similar to Fig. 3 except that the roof extension and counter element are folded.

Fig. 9 is a front elevational view similar to Fig. 4 ex-

cept that the roof extension and counter element are folded.

Fig. 10 is a top plan view showing the trailer as it appears with the roof extension and counter element folded.

The wheels, mast and hitch member shown by means of broken lines are disclosed for illustrative purposes.

I claim:

The ornamental design for a trailer body, as shown and described.
